UNITED STATES PATENT OFFICE.

JEDDIA B. CLARK, OF DUNKIRK, INDIANA, ASSIGNOR TO THE INDIANA GLASS COMPANY, OF DUNKIRK, INDIANA, A CORPORATION OF INDIANA.

DESIGN FOR A TUMBLER OR SIMILAR ARTICLE.

Application filed September 24, 1928. Serial No. 28,253. Term of patent 7 years.

To all whom it may concern:

Be it known that I, JEDDIA B. CLARK, a citizen of the United States, and a resident of the city of Dunkirk, in Jay County and State of Indiana, have invented a new, original, and ornamental Design for a Tumbler or Similar Article, of which the following is a specification, reference being had to the accompanying drawing, forming a part thereof.

The figure is a perspective of a tumbler, showing my new design.

I claim:—

The ornamental design for a tumbler or similar article, as shown.

JEDDIA B. CLARK.
